UNITED STATES PATENT OFFICE.

CHARLES A. LINDSTRÖM, OF ALLEGHENY, PENNSYLVANIA.

SAFETY-CLUTCH FOR DOOR-OPERATING MECHANISMS.

No. 865,714.

Specification of Letters Patent.

Patented Sept. 10, 1907.

Original application filed June 15, 1906, Serial No. 321,794. Divided and this application filed January 11, 1907.
Serial No. 351,820.

To all whom it may concern:

Be it known that I, CHARLES A. LINDSTRÖM, of Allegheny, Allegheny county, Pennsylvania, have invented a new and useful Safety-Clutch for Car-Door-Operating Mechanisms, of which the following is a full, clear, and exact description, reference being had to the accompanying drawings, forming part of this specification, in which—

Figure 1 is a side elevation of a portion of a hopper car embodying my invention; Fig. 2 is a detail sectional view showing the clutch; and Fig. 3 is a detail view also showing the clutch.

This application is a division of application Serial No. 321,794, filed June 15th, 1906.

The invention has relation to a safety device or clutch for use in connection with freight car drop-door operating mechanism; and has for its object the provision of a simple and effective device of this character which is arranged to operate to permit the door-operating quadrant or crank shaft to be released to open the doors, after which such quadrant or crank is free to move without effect upon the operating shaft to which the wrench is attached, thereby obviating the danger or injury by reason of the revolution of the wrench by a sudden rotation of the quadrant or crank arm, due to the opening of the doors.

My invention is applicable to various forms of drop-door operating mechanism, one of which will now be described.

In the drawings, the numeral 2 designates the drop-door of a car which is connected by a rod or link 3 with the crank 4 of an operating shaft 5. The shaft 5 is journaled at its outer end portion in bearings of a bracket 7, and its inner end portion is loosely journaled in the crank-carrying member 8 which is provided with a suitable bearing 9 in the car under-frame. The member 8 which carries the crank 4 is formed with a clutch lug 10 which is adapted to engage with a similar lug 11 carried by a clutch member 12 which is rigidly secured to the shaft 5.

13 is the usual safety pawl, which is arranged to engage a lug or tooth 14 on a collar 15 rigidly secured to the outer projecting end portion of the shaft 5. The purpose of this pawl is to insure the locking of the door in closed position. This locking is, however, effected mainly by the crank 4 coming to and below the center line of the shaft 5 when the door is closed, as shown in Fig. 1.

15' designates the usual safety dog, which locks the pawl 13 in engagement with the tooth 14. One or more additional teeth 16 may be provided on the collar 15 to assist in closing the door by permitting the

operator to change the position of his wrench, if desired. This wrench is applied to the squared-end portion 5^a of the shaft 5.

To open the door, the parts being in the position shown in Fig. 1, the dog 15' is knocked out, and if the pawl 13 cannot then be lifted out of engagement with the tooth 14 by reason of the load resting on it, the operator engages his wrench with the squared portion 60 5^a of the shaft 5, and turns said shaft backwardly until the crank arm 4 is carried by the center. This takes the whole load off the pawl 13, which can now be disengaged without the door opening. The operator now turns the shaft 5 in the opposite direction until the lug 65 11 engages with the other side of the lug 10, and continues to turn sufficiently to raise the crank arm 4 by the center line of the shaft 5. The load acting on the door now opens the latter and causes a partial revolution of the crank arm 4 without turning the shaft 5, 70 the lug 10 moving away from the lug 11. Therefore, no matter how quickly the load may act upon the door after the latter has been released, there is no danger to the operator, who can remove his wrench at leisure.

Various changes may be made in the details of construction and arrangement without departing from the spirit and scope of my invention, since

What I claim is:—

1. In car door operating mechanism, a door-operating crank having a clutch-member forming a part thereof, an independent shaft loosely connected with the clutch member and carrying a co-operating clutch-member, and means for operating the shaft; substantially as described.

2. In car door operating mechanism, a door operating crank having a clutch member fixed thereto, an operating shaft loosely journaled in the hub portion of the crank and carrying a co-operating clutch member, and means for operating the shaft; substantially as described.

3. In car door operating mechanism, a door-operating member normally connected with the door to be operated, an operating shaft journaled in such member, and clutch devices forming a connection between said shaft and operating member and arranged to permit independent movements of the shaft and the member; substantially as described.

4. In car door-operating mechanism, a door-operating member, an independent operating shaft for such member, and a clutch connection between the member and shaft, whereby the shaft may remain stationary during the door opening movement of the member; substantially as described.

5. In car door operating mechanism, a door-operating crank, a shaft and co-operating clutch members carried by the crank and the shaft respectively, and arranged to permit the crank to move independently of the shaft; substantially as described.

6. In car door operating mechanism, a door-operating member normally connected with the door to be operated and having a clutch portion, a shaft having a co-operating clutch portion arranged to engage the first named clutch.

portion in both directions of movement of the shaft, with an intervening lost motion, and means for operating the shaft; substantially as described.

7. In car door operating mechanism, a door operating member normally connected with the door to be operated and having a clutch portion, a shaft having a co-operating clutch portion arranged to engage the first named clutch portion in both directions of movement of the shaft, with an intervening lost motion, means for operating the shaft, and dogging means for the shaft; substantially as described.

8. In car door operating mechanism, a door-operating member, and an operating shaft therefor to initiate the movement of said member and journaled in said member, and clutch devices whereby the shaft remains stationary after initiating such movement; substantially as described. 15

In testimony whereof, I have hereunto set my hand.

CHARLES A. LINDSTRÖM.
